UNITED STATES PATENT OFFICE.

RAY THORNTON, OF NEW BEDFORD, MASSACHUSETTS.

WARP ROLL.

Application filed March 31, 1923. Serial No. 629,100.

To all whom it may concern:

Be it known that I, RAY THORNTON, a citizen of the United States, and a resident of New Bedford, in the county of Bristol and State of Massachusetts, have invented a new and useful Improvement in Warp Rolls, of which the following is a specification.

My invention relates to warp rolls and 10 the like, and its object, generally stated, is to improve the construction of such devices in the manner hereinafter more fully set forth.

Warp rolls as heretofore constructed 15 usually consist of two semi-cylindrical slabs each provided with an oblong groove on its flat side, and rings, bands, or other fastening means arranged on the ends to hold the same together. It is a matter of common experience that in warp rolls so constructed, the square opening running 20 through the center thereof and formed by the oblong grooves disposed as aforesaid in the juxtaposed flat sides of the two slabs 25 making up the roll, becomes distorted when the slabs are subjected to heat and dampness. It has also been found that the two members making up the roll frequently become separated.

It is therefore the specific object of my 30 invention to provide a warp roll, the central aperture of which will not be affected by the action of heat and dampness by virtue of the resisting power of the diverse 35 angular arrangement of the grain of the slabs making up the roll.

Another object of my invention is to provide means whereby the several slabs may 40 be so joined or connected together that it will be practically impossible for them to become separated in ordinary use, the joints between the several members being self-tightening, and not adversely affected by dampness.

With the foregoing objects in view my 45 invention comprises a warp roll made up of four slabs co-extensive in length with the length of the roll, each slab having two straight sides of unequal width disposed 50 at right angles to each other and an arcuate side joining said straight sides, the wider straight side of each slab being arranged at right angles to the wider straight sides 55 of the contiguous slabs and spaced away from the wider straight side of the non-

contiguous slab which is parallel thereto, the narrower straight side of each slab being secured, as for example by a dove-tail tapering throughout the length of the slab to the wider straight side of its contiguous slab, 60 and the roll being bound by the arcuate sides of said four slabs.

In the drawings which accompany and form a part of this specification—

Figure 1 is an end view of a hollow 65 plinth formed by securing the narrower side of each of four identical slabs oblong in cross-section to the wider side of its contiguous slab;

Fig. 2 is an end view of said plinth 70 turned down to circular cross-section to form my improved warp roll; and

Fig. 3 is a plan view of one of the slabs 75 shown in Fig. 1, said view being taken from the point A.

In the particular drawings selected for more fully disclosing my invention 10, 11, 12, 13 are identical slabs oblong in cross-section, each having a dovetailed mortise 14 cut in its wider side, and a dovetailed 80 tenon 15 formed in its narrower side, each mortise and tenon preferably being tapered throughout the length of the slab as indicated in Fig. 3 so that each contiguous pair 85 of slabs is firmly joined by a taper wedge.

Preferably the mortises and tenons are cut by a dovetailing machine of the Lynderman type whereby taper dovetails may be formed with great accuracy and rapidity, each slab being run through the machine 90 in one direction to form the mortise on its wider side, and then in the opposite direction to form the tenon on its narrower side.

When the four slabs are properly shaped, 95 they may be assembled in the manner shown in Figure 1, and the hollow parallelopiped so formed is then centered and turned down to form a cylindrical roll as shown in Fig. 2.

The square-sectioned opening extending 100 through the center of the roll formed in the manner above set forth will not be twisted or distorted by the drying out of the wooden slabs, or by the action of heat and dampness on account of the resistance offered by 105 the slabs, the grain of which is arranged in four general directions. Furthermore the taper wedges by means of which each slab is joined to its two contiguous slabs 110 successfully resist any tendency of shrink-

age or contraction or expansion due to changes in temperature, humidity, etc., to separate the several members.

Having thus described an illustrative embodiment of my invention without however limiting the same thereto, what I claim and desire to secure by Letters Patent is:—

5 A warp roll comprising four slabs co-extensive in length with the length of the roll, each said slab having two straight sides of unequal width disposed at right angles to each other and an arcuate side joining said straight sides, the wider straight side of each slab being disposed at right angles

10 to the wider straight sides of the contiguous slabs and spaced away from the wider straight side of the non-contiguous slab which is parallel thereto, and the narrower straight side of each slab being secured to the wider straight side of its contiguous slab by a dovetail tapering throughout the length of the slab, said roll being bounded by the arcuate sides of said four slabs. 15

20 In testimony whereof, I have hereunto subscribed my name this 26th day of March, 25 1923.

RAY THORNTON.
